Murabick Lytle

UNITED STATES PATENT OFFICE.

MURDICK LYTLE, OF ALLEGHENY, PENNSYLVANIA.

STEERING APPARATUS FOR BARGES IN RIVERS.

Specification of Letters Patent No. 25,429, dated September 18, 1859.

To all whom it may concern:

Be it known that I, MURDICK LYTLE, of the city and county of Allegheny and State of Pennsylvania, have invented a new and

5 Improved Method of Steering Barges in Rivers, &c., While Being Towed by Steam-boats; and I do hereby declare that the following is a full, clear, and exact description of the same, reference being had to the accompanying drawings, forming a part of this specification, in which is represented a steamboat with nine barges in tow, the center barge forward containing the improved apparatus for steering.

10 15 The nature of my invention consists in the application of a wheel to the bow of a barge, so that said wheel shall revolve at right angles to the direction of the barge, in combination with an apparatus for operating said wheel by the power of the propelling boat, as hereinafter specified.

The importance of this invention consists in the fact that large numbers of richly laden barges are lost annually in consequence of the inadequacy of the ordinary way of steering fleets of barges simply by the rudder of the propelling boat.

20 25 30 I am aware that the idea of using a steering wheel at right angles to the direction of the boat, or at the bow is not new. These have been tried and found inefficient to steering a fleet of barges such as a steamer can tow, in consequence of the power being applied near the center of the first barge instead of the front end of the same, as is the case with mine.

To enable others, skilled in the art, to make and use my invention, I will proceed to describe its construction and operation.

35 40 A, represents a steamboat containing the propelling power of a fleet of barges B, two of which are placed on each side of the steamboat and five others forward of these, all securely fastened together and to the steamer.

45 In front of and attached to the bow of the middle forward barge, immediately in front of the steamer, is placed an auxiliary wheel C, which is to aid in steering the fleet in cases of high wind, in meeting with eddies and strong currents where the ordinary rudder of the propelling steamboat is powerless.

55 60 65 to control a larger fleet of barges. The shaft of this wheel, as well as the buckets are on a line with the direction of the barge and consequently prevent little or no obstruction to the forward movement of the barge. To a crank of this shaft D, are attached the pistons of two oscillating steam engines E, E, by which the wheel is operated. These engines are worked by steam conveyed from the boiler of the propelling boat by a steam pipe F, passing forward from the boiler, in some convenient place, to the stern of the barge, where it connects with a similar pipe F', leading from the oscillating engines. These two pipes are united by a ball and socket joint G, containing a passage through the ball for the conveyance of the steam. This form of joint allows sufficient play 70 without obstructing the passage of the steam, for any lateral motion of the barge in steering, or up and down motion caused by the action of the waves. If preferred, a flexible pipe may be used of sufficient 75 strength to withstand the pressure of the steam.

A rope or light chain H, extends from the pilot house of the steerer to a lever I, that opens or closes two valves, by which the 80 steam is let on or off either engine, as occasion may require, thus giving the pilot complete control of the auxiliary wheel, to turn it either way to give the desired direction to the fleet.

85 In the steam pipe near the boiler is placed a valve to shut the steam off or on to the barge, as may be desired. This valve is operated on by an iron rod j, placed in or near the pilot house and under the control of the pilot.

90 What I claim as my invention and desire to secure by Letters Patent, is—

The application of a wheel C, to the bow of a barge, so that said wheel shall revolve at right angles to the direction of the barge, in combination with an apparatus for operating said wheel by the power of the propelling boat, substantially as and for the purposes specified.

MURDICK LYTLE.
